INVENTOR.

UNITED STATES PATENT OFFICE

WILLIAM E. PETERSON, OF SIOUX FALLS, SOUTH DAKOTA

COMBINED DISPLAY AND STORAGE UNIT

Application filed June 23, 1930. Serial No. 463,124.

This invention relates to a combined display and storage unit designed primarily for displaying articles of merchandise in a distinctive and attractive position in store windows, but it is to be understood that a unit, in accordance with this invention, may be employed for displaying and storing articles of merchandise at any place or point for which it may be found applicable, and the invention has for its object to provide, in a manner as hereinafter set forth, a unit of the class referred to so constructed and arranged as to enable for attractive displaying of articles of merchandise and further to permit of the conveniently positioning in and removing of the unit from a store window without disturbing other articles of merchandise arranged in the window for display.

A unit, in accordance with this invention, is so constructed and of a size to enable a plurality of units to be arranged in a store window in sidewise relation, one unit being independent of an adjacent unit whereby the units can be inserted at will in the store window, permitting of the decorator to start at one end of the show window with his first unit and decorate that; and then insert the next unit along side of the first unit and decorate that; and so on until the entire window has been filled with the required number of units to completely fill the window space.

A further object of the invention is to provide, in a manner as hereinafter set forth, a unit of the class referred to so constructed and arranged as to enable the displaying of articles of merchandise at the front and top thereof, as well as at the rear, and further enabling the storing therein of articles of merchandise when occasion requires.

Further objects of the invention are to provide, in a manner as hereinafter set forth, a unit of the class referred to having its front and top disposed in a manner for attractively displaying articles of merchandise and which will be distinctive to the vision of one looking into the show window in which the unit is arranged.

Further objects of the invention are to

provide, in a manner as hereinafter set forth, a combined display and storage unit which is simple in its construction and arrangement, strong, durable, compact, thoroughly efficient for the purpose intended, readily assembled, portable and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a perspective view of a combined display and storage unit in accordance with this invention.

Figure 2 is a view similar to Figure 1 looking toward the rear of the unit.

Figure 3 is a longitudinal sectional view of the unit.

Figure 4 is a section on line 4—4, Figure 3.

Figure 5 is a section on line 5—5, Figure 3.

A combined display and storage unit, in accordance with this invention, includes a pair of vertical side walls 1, 2, each of which has its lower end extending in spaced parallel planes whereby one part of said edge will be positioned above the other part. Each part of said bottom edge is squared and said parts are connected by a vertical shoulder 3. The upper part of the bottom edge of each side wall is indicated at 4 and the lower part at 5. The part 4 is of materially less length than the part 5 and is arranged forwardly of the latter.

Each side wall includes a front edge 6 which extends at a rearward inclination throughout from its lower to its upper end. The lower end of the edge 6 terminates in the forward end of part 4 of the lower edge of the side walls. Each side wall includes a top edge 7 which extends throughout at an upward inclination from its forward to

its rear end. The inclination of the edge 7 is less than the inclination of the edge 6. Each side wall has its back edge formed of a vertical part 9 and a part 10 which extends at a forward inclination from the upper end of the part 9. The upper end of the part 10 merges into the rear end of the edge 7 and the inclination of the part 10 is greater than the inclination of the edge 7, but less than the inclination of the edge 6. The part 9 merges at its lower end into the rear end of the part 5 of the bottom or lower edge of the side wall. The part 9 is of materially less length than the length of part 10 of the rear or back edge of a side wall.

Positioned against the part 4 of the bottom edges of the side walls 1, 2, abutting the shoulder 3 and projecting a substantial distance from the lower corners of walls 1, 2 is a flat, rectangular foot piece 11 having its lower face flush with the part 5 of the bottom edges of the walls 1, 2. The foot piece is disposed transversely of the unit and has its end edges flush with the outer side faces of walls 1, 2. Mounted on the upper face of the foot piece 11 is a vertically disposed nosing 12 of a length corresponding to the length of the foot piece 11. The nosing 12 is arranged a substantial distance forward of the forward lower corners of the walls 1, 2. The nosing 12 has its ends flush with the ends of foot piece 11 and its forward face flush with the forward side edge of foot piece 11. In vertical section the nosing 12 is of rectangular contour. The thickness of the nosing 12 is materially less than the width of the foot piece 11. The foot piece 11 is secured to the side walls 1, 2 and the nosing 12 is secured upon the foot piece 11.

Secured upon the front edges 6 and flush with the outer side faces of the walls 1, 2 is the front 13 of the unit. The wall 13 is disposed at an inclination corresponding to the inclination of the front edges 6 of the walls 1, 2. The top edge of wall 13 is seated upon foot piece 11. The length of the wall 13 corresponds to the length of the front edge 6 of a side wall. The wall 13 connects the walls 1, 2 at the front of the latter. The unit includes a combined support and bracing member for the front and side walls respectively, and which is referred to at 14. The member 14 is disposed at a forward inclination throughout from its bottom to its top edge and is positioned between, as well as being suitably secured to the side walls 1, 2 rearwardly of but in proximity to the shoulder 3. The top edge of the member 14 abuts against the inner face of the front wall 13 intermediate the ends of the latter. The member 14 is of rectangular contour and has its ends abut the inner faces of the walls 1, 2. The bottom edge of member 14 is flush with the part 5 of the bottom edges of walls 1, 2.

The height of the member 14 is materially less than the height at the rear of the unit.

Secured upon the edges 7 of the side walls 1, 2 is the top wall 16 of the unit and which inclines in a manner as that of the inclination of the edges 7. The forward edge of the top wall 16 abuts against the upper edge of the front wall 13 and said wall 16 projects slightly beyond the parts 10 of the rear or back edges of the side walls 1, 2. The wall 16 inclines throughout in an upward direction from its front to its forward edge.

Arranged in abutting relation with respect to the rearwardly projecting portion 17 of top wall 16 is a narrow, cross strip 18 which is secured to the part 10 of the rear edges of the walls 1, 2 and has its ends flush with the outer side faces of such walls. The strip 18 acts as a support for the portion 17 of wall 16 and also as a coupler and brace for the walls 1, 2. Arranged below and in spaced relation to the strip 17, as well as being secured to the parts 10 of the rear edges of the walls 1, 2 is a cross strip 19 which functions as a coupler and brace for the walls 1, 2. The rear face of the strip 18 is flush with the rear edge of the wall 16. The strips 18, 19 are of the same thickness.

Secured between and projecting rearwardly from the walls 1, 2, in proximity to and below the strip 19 is a shelf 20 of rectangular contour and formed of a reduced inner portion 21 having the ends thereof abutting the inner faces of the walls 1, 2 as well as being suitably secured therewith. The outer portion of the shelf 20 and which projects rearwardly from the walls 1, 2, is indicated at 22 and such portion 22 abuts against the part 10 of the rear edges of the walls 1, 2 and has its ends flush with the outer side faces of said walls 1, 2. The shelf 20 extends at an upward inclination throughout from its inner side edge to its outer side edge. Positioned between the side walls 1, 2 at the lower portion of the rear thereof is a pair of superposed, combined bracing and connecting members 23, 24 arranged in spaced relation. The lower face of the member 24 is flush with the part 5 of the bottom edges of the walls 1, 2.

Secured to the outer face of the front wall 13 is a pair of retaining strips 25, 26, and each has its outer face flush with the outer side face of a side wall. The strips 25, 26 extend from the foot piece 11 to the upper end of the wall 13 and are positioned on the side marginal portions of the outer face of wall 13. Secured upon the upper face of wall 16 is a pair of retaining strips 27, 28 and each has its outer face flush with the outer side face of the wall 1 or 2. The strips 27, 28 at their forward ends abut

the upper ends of the strips 25, 26 respectively. The rear ends of the strips 27, 28 are flush with the rear edge of the wall 16. The strips 27, 28 are positioned on the side 5 marginal portions of the upper face of the wall 16.

Mounted upon the shelf 20 and positioned against the strips 18, 19 and extending a substantial distance above the top wall 16 10 is a lattice bracket 29.

When a plurality of units are arranged in sidewise abutting relation the shelves 20 abut to form what may be termed a continuous shelf for display purposes. The shelf 15 20 of each unit also provides a shelf for display purposes. The walls 13, 16 constitute a pair of surfaces or floors for display purposes disposed at an angle with respect to each other. The rear of the unit 20 is open for receiving stock of goods displayed upon the front, top and rear of the unit. The rear of the unit is left open if possible for the display of the goods placed therein from the inside of the store. The 25 unit can be constructed of any suitable material. The length, width and height of the unit can be as desired. The angular disposition of the walls 13, 16 relatively to each other can be as desired.

30 What I claim is:—

1. A combined display and storage unit including a pair of side walls having inclined front and inclined top edges, a front wall disposed at an inclination corresponding to the inclination of said front edges, a top wall disposed at an inclination corresponding to the inclination of said top edges, said front and top walls being secured to said side walls, said front edges inclining 35 rearwardly from the bottom to the top thereof, said top edges inclining upwardly from the forward to the rear edges thereof, a foot piece secured to and projecting from the bottom of said side walls at the forward 40 ends of said walls, a nosing secured upon said foot piece and spaced from the lower end of said front wall, a combined coupling and bracing member interposed between and secured to said side walls and positioned 45 against the inner face of said front wall, a pair of spaced retaining strips secured to the outer face of said front wall, and a pair of spaced retaining strips secured upon the upper face of said top wall.

50 2. A combined display and storage unit including a pair of side walls having inclined front and inclined top edges, a front wall disposed at an inclination corresponding to the inclination of said front edges, a top wall disposed at an inclination corresponding to the inclination of said top edges, said front and top walls being secured to said side walls, said front edges inclining rearwardly from the bottom to the 55 top thereof, said top edges inclining up-

wardly from the forward to the rear edges thereof, a foot piece secured to and projecting from the bottom of said side walls at the forward ends of said walls, a nosing secured upon said foot piece and spaced from the lower end of said front wall, a pair of spaced retaining strips secured to the outer face of said front wall, a pair of spaced retaining strips secured upon the upper face of said top wall, and a shelf secured 60 between said side walls and projecting rearwardly therefrom.

3. A combined display and storage unit including a pair of side walls having inclined front and inclined top edges, a front wall disposed at an inclination corresponding to the inclination of said front edges, a top wall disposed at an inclination corresponding to the inclination of said top edges, said front and top walls being secured to said side walls, said front edges inclining rearwardly from the bottom to the top thereof, said top edges inclining upwardly from the forward to the rear edges thereof, a foot piece secured to and projecting from the bottom of said side walls at the forward ends of said walls, a nosing secured upon said foot piece and spaced from the lower end of said front wall, and a shelf secured 65 between and projecting rearwardly from said side walls, said shelf extending at an upward inclination throughout from its inner to its outer edge.

4. A combined display and storage unit including a pair of side walls having inclined front and inclined top edges, a front wall disposed at an inclination corresponding to the inclination of said front edges, a top wall disposed at an inclination corresponding to the inclination of said top edges, said front and top walls being secured to said side walls, said front edges inclining rearwardly from the bottom to the top thereof, said top edges inclining upwardly from the forward to the rear edges thereof, a foot piece secured to and projecting from the bottom of said side walls at the forward ends of said walls, a nosing secured upon said foot piece and spaced from the lower end of said front wall, a combined coupling and bracing member interposed between and secured to said side walls and positioned against the inner face of said front wall, and a shelf secured between and projecting rearwardly from said side walls, said shelf extending at an upward inclination throughout from its inner to its outer edge.

In testimony whereof, I affix my signature hereto.

WILLIAM E. PETERSON.
